DESIGN FOR A UNIVERSAL HEAD FOR A
PORTABLE POWER DRILL

Albert C. Koett, Cincinnati, Ohio, assignor to The
Kett Tool Company, Cincinnati, Ohio

Application November 22, 1946, Serial No. 135,005

Term of patent 14 years

(Cl. D54—14)

To all whom it may concern:

Be it known that I, Albert C. Koett, a citizen of the United States, residing at Cincinnati, in the county of Hamilton and State of Ohio, have invented a new, original, and ornamental Design for a Universal Head for a Portable Power Drill, of which the following is a specification, reference being had to the accompanying drawing, forming a part thereof.

Figure 1 is a side elevation of the universal head for a portable power drill, embodying my new design.

Figure 2 is a top plan view thereof.

Figure 3 is a rear view looking endwise of the tool.

Figure 4 is a front view looking endwise of the tool.

Figure 5 is a perspective view, showing my new design.

I claim:

The ornamental design for a universal head for a portable power drill, substantially as shown.

ALBERT C. KOETT.
